(57) **CLAIM**

The ornamental design for a lint roller cover, as shown and described.

DESCRIPTION

FIG. 1 is a perspective view showing the new design for a lint roller cover;

FIG. 2 is a front view thereof;

FIG. 3 is a rear view thereof;

FIG. 4 is a top view thereof;

FIG. 5 is a bottom view thereof;

FIG. 6 is a left side view thereof;

FIG. 7 is a right side view thereof; and,

FIG. 8 is a perspective view thereof showing the lint roller cover with a lint roller.

The portions in Figures shown in broken lines form no part of the claimed design.
